US0D1039766S

(12) United States Design Patent (10) Patent No.: US D1,039,766 S
(45) Date of Patent: * Aug. 20, 2024

(54) PATTERNED BASE FOR ARTIFICIAL LASH EXTENSION

(71) Applicant: Lashify, Inc., North Hollywood, CA (US)

(72) Inventor: Sahara Lotti, North Hollywood, CA (US)

(73) Assignee: Lashify, Inc., North Hollywood, CA (US)

() Term: 15 Years

(21) Appl. No.: 29/922,395

(22) Filed: Dec. 21, 2023

Related U.S. Application Data

(62) Division of application No. 29/901,882, filed on Sep. 6, 2023.

(57) CLAIM

The ornamental design for a patterned base for an artificial lash extension, as shown and described.

DESCRIPTION

FIG. 1 is a top left perspective view of a patterned base for an artificial lash extension in accordance with the claimed design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines consisting of evenly spaced lines in the figures show portions of the artificial lash extension that form no part of the claimed design. The dash-dot lines illustrate boundaries of the claim design and form no part of the claimed design.

1 Claim, 5 Drawing Sheets
